UNITED STATES PATENT OFFICE.

PAUL C. BUTTE, OF SAN FRANCISCO, CALIFORNIA.

ELECTRIC SWITCH.

Application filed March 31, 1925. Serial No. 19,621.

The invention relates to electric switches and particularly to so-called safety switches of compact construction for switchboard mounting in which fuses are combined with the switch, means being provided for preventing access to the fuses while the switch is closed.

An object of the invention is to provide a safety switch in which both the switch and the fuses are enclosed, means being provided for insuring the closing of the fuse chamber prior to the closing of the switch.

Another object of the invention is to provide a safety switch in which access to the fuses may not be had until after the switch has been fully opened.

A further object of the invention is to provide a safety switch having a cover over the fuse casing and a cover over the switch casing, the covers being so arranged that the initial closing movement of the switch cover moves the fuse cover to closed position in advance of the closing of the switch.

Another object of the invention is to provide means for preventing contact of the hand of the operator with the live contacts of the switch, when the switch casing is open, and for preventing burning by the arc that is formed as the switch is opened.

The invention possesses other advantageous features, some of which with the foregoing, will be set forth at length in the following description, where I shall outline in full that form of my invention which I have selected for illustration in the drawings accompanying and forming part of the present specification. In said drawings I have shown one form of switch embodying my invention, but it is to be understood that I do not limit myself to such form, since the invention, as set forth in the claims, may be embodied in a plurality of forms.

Referring to said drawings:

Figure 1 is an elevation of the safety switch of my invention in closed position.

Figure 2 is a side elevation of the switch in closed position.

Figure 3 is a cross section taken on the line 3—3 Figure 1, showing the switch in closed position, in full lines, and showing the position of the parts when the switch is open in dotted lines.

Figure 4 is a fragmentary vertical section of the switch taken on the line 4—4 Figure 3.

The switch of my invention comprises a

switch and fuses, both the switch and the fuses being enclosed to prevent accidental contact therewith. The switch and the fuses are enclosed in one chamber, which is provided with two covers, movement of one cover serving to open the switch and movement of the other cover serving to permit access to the fuses. The two covers are arranged in operative relationship, so that the cover of the fuse chamber may not be opened or may not remain open during the time that the switch is closed and the cover of the switch extends over the switch blades to prevent accidental burning by the arc which is formed as the switch is opened.

The switch comprises a panel 2 on which the various elements of the switch are mounted. Secured to the panel are a plurality of switch posts 3 on which the switch blades 4 are pivoted. The switch blades are connected together by a cross bar 5 of insulating material, so that the plurality of blades are simultaneously moved into and out of engagement with the switch contacts. The switch contacts 6 are mounted on the panel in position to be engaged by the switch blades and, in order to prevent contact of the hand with the switch contacts, they are disposed in a box-like structure 7 of insulating material, secured to the panel and extending transversely thereof. The structure 7 is provided on its side and top with slots in alignment with the contacts to permit the switch blades to be moved into engagement with the contacts. The contacts are thus enclosed in a box so that accidental contact of the hand therewith is prevented. Arranged on the panel at that side of the box 7 which is remote from the switch post 3, is a plate 8 of insulating material which closes the far side of the box and which preferably extends above the box 7, to prevent accidental contact with the contacts 6 by a person inserting his hand into the switch from above when it is open. The contacts 6 are therefore thoroughly shielded so that the possibility of accidental contact of the hand therewith is reduced to a minimum.

Mounted on the panel adjacent and preferably below the switch are a plurality of fuse clips 9 which are normally operatively connected by removable cartridge fuses 12. In the usual operation of electrical apparatus, the fuses frequently burn out, requiring the removal of the burned out fuses and the insertion of new fuses. When the switch is

closed, the upper fuse clip 9 is "hot" and many accidents have occurred by persons bringing their hands into contact with the "hot" clip while they are endeavoring to change the fuses. One of the objects of my invention is to provide a switch of such character that access to the fuses may not be had when the switch is closed.

Secured to the panel and enclosing the fuses and fuse clips is a casing comprising the side walls 13 and the bottom wall 14. The casing is provided with a cover 15 which is hinged to the side walls 13 on the pivot 16, the cover being movable about the pivot to permit access to the fuses. The switch is covered by a hood 17 having side walls 18, a top wall 19 and a front wall 21. The hood is pivoted to the side walls 13 of the casing by the pins 22 and is provided with a handle 23, so that it may readily be moved. The cross bar 5 is connected to the front wall 21 of the hood by the strap 24 secured to the front wall and extending over the cross bar, so that the switch blades move substantially simultaneously with the movement of the hood. This construction permits sliding movement of the cross bar 5 in the strap 24, which is caused by the non-concentric relation of the pivots of the switch blades and the pivots 22.

Means are provided for preventing the opening of the cover 15 when the hood 17 is in such position that the switch blades are in engagement with the switch contacts 6 and for causing a closing movement of the cover 15 when the hood is moved in a direction to close the switch. The upper end of the cover 15 extends beyond the pivot 16 and the hood is provided with means which cooperate with the upper end of the cover to cause the cover to be closed whenever the switch is closed. Secured to the front face 21 of the hood is a plate 25 having lugs 26 thereon, the outer faces of which are concentric with the axis of the pins 22. When the hood is closed the upper edge of the cover 15 is in abutting or substantial abutting contact with the curved outer faces 27 of the lugs and, since the upper edge of the cover extends above the axis of the pin 16, the lugs lie in the path of movement of the upper edge of the cover in the opening movement of the cover, so that the cover may not be opened. The curved faces 27 of the lugs are of such length that they do not move out of the path of the upper end of the cover, in the opening movement of the hood, until the switch blades 4 have been moved out of engagement with the contacts 6. When the switch blades have been moved out of engagement with the contacts 6, the hood is in such position that the lugs 26 are moved out of the path of the upper edge of the cover, as shown in dotted lines in Figure 3, so that the cover may be

opened. When the cover is open, the upper end thereof lies in front of the upper surfaces of the lugs, so that the initial closing movement of the hood operates, by virtue of the relative positions of the lugs and the upper end of the cover 15, to close the cover 15 before the hood has been moved a sufficient distance to bring the switch blades into engagement with the contacts 6.

In some instances, it may be necessary for a skilled electrician to obtain access to the fuses without opening the circuit and, for this purpose, the plate 25 is mounted so that by proper manipulation it may be moved vertically, moving the lugs out of the path of the upper edge of the cover. For this purpose the plate 25 is secured to the head by screws 28, which extend through slots 29 in the plate. By loosening the screws, the plate may be pushed upward and, when in such position, the cover 15 may be opened during the time that the switch is closed.

I claim:

1. In an apparatus of the class described, a panel, switch contacts mounted on said panel, switch blades cooperating with said contacts, a casing secured to the panel, a hood pivoted on the casing and adapted to cover said contacts and blades, a cover on said casing, normally fixed means arranged on the hood to coact with the cover to lock the cover in closed position when said hood is in closed position, and means for permitting movement of said normally fixed means with respect to said hood for allowing the cover to be opened when the hood is in closed position.

2. In a device of the class described, a panel, switch means arranged on said panel and including elements having uninsulated surfaces, pivotally mounted means movable to a closed position to shield the uninsulated surfaces of said switch elements, said last recited means being movable to an open position to expose said uninsulated surfaces and allow access to the same, a casing secured to said panel, a pivotally mounted cover over said casing and movable to either an open or closed position, means engaging said cover for moving the same to its closed position upon manual movement of said pivotally mounted means to its closed position and means positioned by the closing of said pivotally mounted member for locking said cover in its closed position.

3. In an apparatus of the class described, a panel, switch contacts mounted on said panel, switch blades cooperating with said contacts, a casing secured to the panel, a hood pivoted on said casing and connected to the switch blades, movement of the hood away from the panel serving to open the switch, a hinged cover on said casing and means on the hood coacting with the cover whereby movement of the hood to switch

closing position moves the cover to closed position and locks the cover in such position.

4. In an apparatus of the class described, 5 a panel, switch contacts mounted on said panel, switch blades cooperating with said contacts, a casing secured to the panel, a hood pivoted on said casing and connected to the switch blades, movement of the hood 10 away from the panel serving to open the switch, a hinged cover on said casing and means for preventing the movement of the hood to switch closing position when the cover is in open position.

15 5. In an apparatus of the class described, a panel, switch contacts mounted on said panel, switch blades cooperating with said contacts, a casing secured to the panel, a hood pivoted on said casing and connected 20 to the switch blades, movement of the hood away from the panel serving to open the switch, a hinged cover on said casing, a lug mounted to move with the hood, said lug being in engagement with the end of 25 the cover when the switch is closed, to prevent opening said cover, movement of the hood to open switch position serving to move the lug out of the path of the end of the cover, so that the cover may be moved 30 to open position.

6. In an apparatus of the class described, a panel, switch contacts mounted on said panel, switch blades cooperating with said contacts, a casing secured to the panel, a hood pivoted on said casing and connected 35 to the switch blades, movement of the hood away from the panel serving to open the switch, a hinged cover on said casing, a lug mounted to move with the hood, said 40 lug being in engagement with the end of the cover when the switch is closed, to prevent opening said cover, movement of the hood to open switch position serving to move the lug inward and out of the path 45 of the end of the cover, so that the cover may be moved to open position, the lug being so arranged that with both hood and cover open, the edge of the cover lies in the path of hood closing movement of the 50 lug, whereby closing movement of the hood moves the cover to closed position.

7. In an apparatus of the class described, a panel, switch contacts mounted on said panel, switch blades cooperating with said 55 contacts, a casing secured to the panel, a hood pivoted on said casing and connected to the switch blades, movement of the hood

away from the panel serving to open the switch, a hinged cover on said casing adapted to be moved to open position when 60 the hood is in open switch position and means associated with the hood operative upon initial closing movement of the hood to close the cover, so that the cover is closed in advance of the switch. 65

8. In an apparatus of the class described, a panel, switch contacts mounted on said panel, switch blades cooperating with said contacts, a casing secured to the panel, a hood pivoted on said casing and connected to the switch blades, movement of the hood away from the panel serving to open the switch, a cover on said casing and normally fixed movable means on the hood arranged to coact with the cover to hold the cover in 70 locked position, when the hood is in switch closing position, said means being movable to permit the cover to be opened when the hood is in switch closing position. 75

9. In an apparatus of the class described, 80 a panel, switch means mounted upon said panel, a casing mounted on said panel, a hood pivotally mounted on said casing at a point spaced from said panel and adapted to be moved to enclose said switch means, 85 a cover on said casing, means adjacent the upper end of said cover for pivotally mounting the same to said casing at a point farther removed from said panel than the pivotal mounting for said hood, said upper 90 end being adapted to move upward and inward when said cover is opened, and means on said hood for engaging said upper end when said hood is in closed position to lock said cover in closed position. 95

10. In an apparatus of the class described, a panel, switch means mounted upon said panel, a casing mounted on the panel, a hood pivotally mounted on the casing and adapted to enclose parts of the switch when 100 in closed position, a cover pivotally mounted on the casing on an axis parallel to the pivotal mounting of the hood, and an arcuate locking member mounted on the hood and having its surface concentric to the pivotal 105 mounting of the hood and engaging a portion of the cover, whereby the cover is locked in closed position until the hood is moved a substantial distance towards its open position. 110

In testimony whereof, I have hereunto set my hand.

PAUL C. BUTTE.
